UNITED STATES PATENT OFFICE.

RODOLPHE EDGARD MATHOT, OF BRUSSELS, BELGIUM.

FUEL-SUPPLY REGULATOR FOR INTERNAL-COMBUSTION ENGINES.

1,373,666.

Specification of Letters Patent.

Patented Apr. 5, 1921.

Application filed May 13, 1919. Serial No. 296,952.

To all whom it may concern:

Be it known that I, RODOLPHE EDGARD, MATHOT, a subject of the King of Belgium, of Brussels, Belgium, have invented certain new and useful Improvements in Fuel-Supply Regulators for Internal-Combustion Engines, of which the following is a specification.

This invention relates to improvements in mechanism for regulating the timing of the fuel supply in liquid fuel engines.

My invention consists in an improved mechanism which affords the possibility of timing the fuel supply or injection by moving the fuel-supply pump or pumps around the operating or cam-shaft without changing or effecting the setting of the governor. The proper angular shifting of said pump or pumps also answers the requirements of 20 a reversible engine.

The invention is based on the principle that the moment of maximum compression and consequently of maximum temperature in the engine cylinder is the most favorable 25 for effecting the combustion, and also that the highest velocity of injection insures the best atomization of the fuel.

It will be seen that the method of governing hereinafter described realizes the 30 above mentioned desiderata and also allows rapid regulation in accordance with the nature of the fuel, while it does not transmit any detrimental reactions to the governor.

The accompanying drawings illustrate a 35 preferred embodiment of the invention and in said drawings:—

Figure 1 is a diagrammatic longitudinal section of a fuel-pump and governing device as applied to a horizontal engine.

40 Fig. 2 is a cross-section of the same arrangement.

Fig. 3 is a partial section of a set of pumps as applied for instance to a vertical multi-cylinder engine.

45 Fig. 4 is a detail view of a regulating cam or bush shown in Figs. 1 and 3.

In said drawings, C designates the pump barrels carried by a frame or casing D movable around a fixed bushing E which may 50 be part of the engine frame and in which the cam shaft G rotates freely. The casing D can turn around said shaft and be adjusted to the required position, for instance by means of a turn-buckle H as shown in 55 Figs. 1 and 2, or by a rack and pinion or the like.

F are spring-loaded plungers operated by the cam 1 keyed to the shaft G. In Figs. 1 and 2, the cam is of the regular kind with a cylindrical boss, while in the case of a multi-cylinder engine, as in Fig. 3, the cam may be formed of a disk 1 provided with a cam or boss which operates the several pumps successively, and is so mounted on the shaft as to allow the pump or pumps to be located 60 alongside of or in the same plane as said shaft.

The plungers F are operated through a roller J which, as shown in Figs. 1 and 2, may be carried by a pivoted bracket K to 70 take up the side thrust, or may be guided in an enlarged and suitably slotted part of the barrel as in Fig. 3.

L are by-pass or regulating-valves operated by the governor M through the recessed 75 cam or bush N against which rollers at the ends of the valve stems are pressed by light coil springs.

The bush N is made in two halves, one of which is provided with the cam or recess, 80 both halves being connected to the governor M through a sleeve N¹ which is provided with a feather key. The bush N is connected to this governor sleeve in such manner as to be readily adjustable and removable by means of bolts and slotted holes or the like.

O are the delivery-valves to the working cylinder of the engine, and P are the inlet-valves to the pumps, Q being by-pass valves 90 by which the surplus oil is returned to the reservoir. In Fig. 3 this by-pass Q is provided with a spring-loaded plug R, and the inlet to the pumps takes place either through the by-pass or straight through the adjoining check-valve P when the plug R is forced down.

The operation is as follows:—

Taking one of the pumps, during the first period of the inward stroke of the plunger 100 F, the regulating-valve L is kept open (see the left-hand portion of Fig. 3) to allow the oil admitted during the suction stroke to return back to the reservoir. As soon as the regulating-valve L closes, the remaining 105 oil is supplied to the corresponding working cylinder of the engine as shown in Fig. 2 and at the right hand of Fig. 3. The amount of oil so supplied thus depends on the duration of opening of said regulating-valve. The operation of said valve is under 110 the control of the governor M through the

bush N, which rotates with the cam-shaft G, so that the roller of valve L moves on the periphery of the bush. It will be understood that the circumferential extent of the 5 cam or recess of the bush N varies from one end to the other, so that as the bush is moved longitudinally by the action of the governor, the time during which the valve L remains open will be increased or decreased. Owing 10 to the pressure of its spring, the valve L will close as soon as allowed to drop into the recess of the bush. The valve L is thus not positively operated by the bush N whereby no reactionary effect is exerted on the 15 governor. Owing also to the trapezoidal form of the recess in the bush, the valve L will be caused to close earlier or later according to the position imparted to said bush.

The injection to the engine will be thus 20 caused to commence earlier or later according to the load.

The variable quantity supplied to the engine is thus the result of the variable commencement of the injection, while the 25 termination of said injection is constant and depends upon the end of the stroke of the plunger, that is to say, when the outer portion of the rise of the cam is acting on the plunger. The injection occurring while the 30 top portion of the cam is operative, maximum velocity will be provided for the atomization of the fuel.

It will be seen that by an angular movement of the casing D carrying the fuel pump 35 or pumps, the timing of the injection period can be varied to suit the grade of fuel, or if needed, to a certain extent the speed of the engine. As the position of the bush N is not altered relatively to the pump cam I, 40 the foregoing adjustment leaves the governing unaltered.

Also by revolving the casing D through the required angle, the timing of the injection period can be adjusted to suit a reversion- 45 ble engine, as shown in Fig. 3.

In case of multi-cylinder engines also as in Fig. 3, for the purpose of priming the fuel pipes leading to the cylinders, the plug R can be pushed down, compelling the fuel 50 to pass through the check-valve P, which allows the corresponding pump to be operated by hand.

The governing bush N may be operated as well by hand as by governor.

55 What I claim as my invention and desire to secure by Letters Patent of the United States is:—

1. In fuel regulating mechanism for liquid fuel engines, the combination of a fuel 60 injector, means for regulating the supply of fuel to said injector, separate operating devices for said injector and regulating means, a shaft supporting said devices and a governor controlling the operation of said regulating means, the injector and regulating means

being connected to turn in unison for adjustment about the axis of said shaft whereby the timing of the fuel supply may be regulated without affecting the setting of the governor. 70

2. In fuel regulating mechanism for liquid fuel engines, the combination of a fuel pump, by-pass valve mechanism formed as a unitary part of said pump, an operating shaft, means on said shaft for separately operating said pump and by-pass valve, and a governor adapted to act on the valve operating means, said pump and by-pass valve being connected to turn in unison for adjustment about the axis of the operating shaft to vary the periods of actuation 75 of said pump and valve without affecting the setting of the governor. 80

3. In fuel regulating mechanism for liquid fuel engines, the combination of a fuel 85 injector, means for regulating the supply of fuel to said injector, separate operating devices for said injector and regulating means, a shaft supporting said devices and a governor controlling the operation of 90 said regulating means, the injector and regulating means being connected to turn in unison for adjustment about the axis of said shaft whereby the timing of the fuel supply may be regulated without affecting the 95 setting of the governor, the range of said circumferential adjusting movement of the injector and regulating means being sufficient to adapt the timing of the fuel supply to the requirements of a reversible en- 100 gine.

4. In fuel regulating mechanism for liquid fuel engines the combination of a fuel pump, by-pass valve mechanism formed as a unitary part of said pump, an operating shaft, a cam on said shaft for actuating the pump, a detachable bush also on said shaft and having a recessed portion adapted to permit non-positive closing of the by-pass valve and means adapted to control displacement of said bush relatively to said by-pass valve. 110

5. In a fuel regulating mechanism for liquid fuel engines the combination of a fuel pump, a spring-loaded by-pass valve 115 adapted to regulate the supply of fuel to said pump, an operating shaft, a cam on the latter for actuating the pump, a detachable bush movably mounted on the shaft and having a recessed portion adapted to permit 120 non-positive automatic closing of the by-pass valve by its spring, a governor adapted to control displacement of said bush in relation to the valve, said governor receiving no reactionary effects from the closing of 125 the by-pass valve, the latter and the pump being adjustable in unison about the axis of the operating shaft whereby the timing of the fuel supply may be regulated without affecting the setting of the governor. 130

6. In a fuel regulating mechanism for liquid fuel engines the combination of a fuel-pump, a by-pass valve adapted to regulate the supply of fuel to said pump, an operating shaft, a cam on said shaft for actuating the pump, a cam member movably mounted on said shaft for controlling said by-pass valve and a governor adapted to control the movements of said cam member whereby the valve is caused to close automatically after pressure takes place in the pump and opens after such pressure is relieved, the control of the valve by the cam member being such that no reaction on the 10 governor is produced.

7. In fuel regulating mechanism for liquid fuel engines the combination of a fuel-pump, a by-pass valve adapted to regulate the supply of fuel to the pump, an operating shaft, separate means on the latter for actuating the pump and valve, a governor adapted to control the valve actuating means, the pump and valve being adjustable in unison about the axis of the operating 20 shaft, means of communication between the pump and the engine cylinder and means 25

for priming said communication when operating the pump by hand.

8. In fuel regulating mechanism for multi-cylinder liquid fuel engines the combination of a plurality of fuel-pumps, a by-pass valve for each pump adapted to regulate the supply of fuel to its respective pump, an operating shaft having its axis in a plane containing the axes of the pumps, 30 a single cam on said shaft for successively actuating the pumps, a cam member movably mounted on the shaft for controlling the by-pass valves and a governor adapted to control said cam-member, the pumps and 40 by-pass valves being adjustable in unison about the axis of the operating shaft whereby the timing of the fuel supply may be varied without affecting the setting of the governor.

In witness whereof I have signed this specification in the presence of two witnesses.
